UNITED STATES PATENT OFFICE.

GEORGE STREAT, OF NEW YORK, N. Y.

DESIGN FOR A TEXTILE FABRIC.

SPECIFICATION forming part of Design No. 16,379, dated November 10, 1885.

Application filed August 24, 1885. Serial No. 175,156. Term of patent 3½ years.

To all whom it may concern:

Be it known that I, GEORGE STREAT, a citizen of the United States, residing at the city of New York, county of New York, and State 5 of New York, have invented and produced a new and original Design for Textile Fabrics for Men's and Women's Wear, of which the following is a specification, reference being had to the accompanying drawings, forming 10 part thereof.

I expect to employ my design especially in printing calicoes and similar fabrics.

The leading features of my design consist in a stripe, hereinafter more fully described, 15 parallel to and alternating with a stripe which is crossed at right angles by alternate light and dark lines, which are blended into each other by shading.

a a a in the drawings are stripes which are 20 uniform from end to end, and may be a solid block of color, as in Fig. 1, or of the form of dots or pin-points applied closely together, as in Fig. 2.

b b b are stripes alternating with the stripes 25 *a*. These stripes are crossed at frequent intervals by lines *c c c*, alternately light and

dark. At the division between each dark line and its adjacent light line it is shaded off, as indicated in the drawings.

The general color or tint of the stripes *b b* 30 is immaterial, so long as it is applied in shaded dark and light lines, as already described.

I have illustrated the stripes *a* as being of the same shade and color from end to end; but the shade or color in these stripes may be 35 made in so'ld blocks of alternating shades; or these blocks may be all of the same color, but distinguished from each other by having a block of the color applied in the pin-points alternating with a block of solid color. 40

I claim—

The design for textile fabrics herein shown and described, the same consisting of the stripes *a a*, parallel to and alternating with the stripes *b b*, the latter being crossed at right 45 angles by alternate light and dark lines, which are blended into each other by shading, substantially as described.

GEO. STREAT.
